UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A COMPANY OF GREAT BRITAIN.

STEAM-TURBINE.

1,325,135.

Specification of Letters Patent. Patented Dec. 16, 1919.

Application filed February 18, 1918. Serial No. 217,948.

To all whom it may concern:

Be it known that I, KARL BAUMANN, a citizen of the Confederation of Switzerland, and a resident of Urmston, in the county of 5 Lancaster, England, have invented a new and useful Improvement in Steam-Turbines, of which the following is a specification.

This invention relates to steam turbines and more especially to removable nozzle 10 boxes employed in such turbines for admitting steam to the first row of moving blades.

One object of the invention is to provide improved constructions of nozzle boxes adapted to be located within the turbine 15 cylinder and to communicate with the steam supply pipe or pipes through a comparatively small opening or openings in the end or side of the turbine cylinder and by means of which steam may if desired be admitted 20 over substantially the whole circumference of the first row of moving blades of the turbine. The openings in the cylinder may be restricted to approximately the size of the port openings necessary for the admission of 25 steam to the nozzle boxes and thus reduce weakening of the cylinder arising from the openings to a minimum.

In the accompanying drawings Figure 1 is a sectional view through the high pressure 30 end of a turbine cylinder having two nozzle boxes constructed in accordance with this invention located therein. Fig. 2 is a part similar view showing a modified construction of nozzle box, Fig. 3 being a sectional view on the line III—III of Fig. 2. Fig. 4 is a sectional view similar to Fig. 1 showing another form of nozzle box. Fig. 5 is a view similar to the lower half Fig. 1 illustrating an alternative method of supporting and guiding the nozzle box in position, Fig. 6 being a sectional view on the line VI—VI of Fig. 5.

Referring to Fig. 1, the nozzle box 7 is formed, as shown, as a curved hollow chamber closed at its ends and having a steam inlet 8 located at an intermediate point along its length. The inlet 8 is provided with a flange 12 by means of which the nozzle box 7 is secured within the cylinder 10, in such 45 a position that said inlet registers with a steam admission port 9 in the side of the turbine cylinder 10, and a steam supply pipe 11. The bolts 13, by means of which the flange 12 is attached to the turbine cylinder 10, are preferably arranged as shown so

that the joint between the inlet 8 of the nozzle box and the turbine cylinder 10 can be tightened from the exterior of the turbine cylinder.

Guides for maintaining the nozzle box 7 in its proper position within the turbine cylinder with respect to the moving blades are provided at either end of the nozzle box 7 each comprising a lug 14 on the nozzle box furnished with a pin 15 adapted to slide 60 within a projection 16 on the turbine cylinder. Said guides are so arranged that the axes of the pins 15 are directed toward the inlet 8 which is attached to the cylinder 10 and permit of free movement of the nozzle box due to expansion taking place in either direction from the inlet 8. As shown, the guiding means 14, 15 and 16 only permit movement of the nozzle box to take place in a plane substantially perpendicular to the 70 turbine axis so that the relative position of the nozzles in the nozzle box 7 with respect to the moving blades with which said nozzles coöperate will be constantly maintained 75 uniform.

The nozzle box 7 in the lower half of Fig. 1, is similar to the nozzle box located in the upper half of the turbine cylinder except that the inlet 8 is placed nearer one end of the box than the other in order that the admission port 9 and steam pipe 11 may be located in a convenient part of the turbine cylinder. With this arrangement the guiding pin 15 which slides in a lug 17 on the nozzle box 7 may conveniently be inserted, 80 as shown, through the cylinder wall 10, with its axis directed toward the inlet 8 by which the nozzle box is attached to the cylinder.

In Figs. 2 and 3 a nozzle box is shown similar to that illustrated in the upper part 95 of Fig. 1 except that the inlet 8 is adapted to register with a steam admission port 9 located in the end of the cylinder 10.

The nozzle box shown in Fig. 4 is in the form of a hollow annulus having a single 100 steam inlet 8 secured to the steam admission pipe 11, the latter being bolted to the turbine cylinder 10.

Instead of securing the nozzle box in position within the cylinder by means of its 105 steam inlet, as shown in Figs. 1 to 4, the nozzle box may be attached to the turbine cylinder as illustrated in Figs. 5 and 6 by a lug 18 formed on or secured to the nozzle box and bolted to a boss 19 formed on 110

the cylinder 10. Where this method of attachment is employed the steam inlet 8 to the nozzle box is conveniently arranged to slide within a prolongation of the steam admission port 9. In this way movement of the nozzle box 7, due to expansion, may take place and the provision of a guide or guides, such as are shown in Figs. 1 to 4, for maintaining the nozzle box in its proper relative position in regard to the moving blades, is rendered unnecessary.

I claim as my invention:

1. In a steam turbine of the parallel flow type, a curved hollow steam chamber having an admission port registering with the turbine inlet port and means constructed so as to support said steam chamber in position within the turbine casing in such manner that it is allowed free movement for expansion and contraction independently of the turbine casing.

2. In a parallel flow steam turbine, a removable nozzle box formed as a curved hollow chamber having an inlet port at an intermediate point along its length and adapt-

ed to be located entirely within and attached to the turbine casing and means for supporting said box within the turbine casing constructed and arranged so as to allow the same to freely expand and contract independently of the turbine casing.

3. In combination with the casing of a steam turbine having an inlet for steam, a removable nozzle box formed in the nature of a curved hollow chamber having a steam inlet at a point intermediate its ends and located entirely within the turbine casing, and supporting means for said nozzle box constructed and arranged to permit free movement thereof due to expansion in either direction from the steam inlet.

4. A structure as claimed in claim 3 in which the supporting means include pins, the axes of which are directed toward the steam inlet.

In testimony whereof I have hereunto subscribed my name this fourth day of January, 1918.

KARL BAUMANN.
